H. F. JUERGENS

BEAD FOR JEWELRY

Filed July 24, 1922

Inventor
Henry F. Juergens

By Horatio E. Bellows

Attorney

UNITED STATES PATENT OFFICE.

HENRY F. JUERGENS, OF PROVIDENCE, RHODE ISLAND.

BEAD FOR JEWELRY.

Application filed July 24, 1922. Serial No. 576,989.

To all whom it may concern:

Be it known that I, HENRY F. JUERGENS, a citizen of the United States, residing at Providence, in the county of Providence and State of Rhode Island, have invented certain new and useful Improvements in Beads for Jewelry, of which the following is a specification.

My invention relates to ornamental beads primarily designed for jewelry.

The essential objects of my invention are to simulate stones, gems, and ornaments of an expensive character in an inexpensive material; to diminish weight; insure beauty; and to attain these ends in an inexpensive structure.

A further essential object is to construct beads in a simple, facile, and inexpensive manner.

To the above ends essentially my invention consists in such parts and in such combinations of parts, and in such steps and in such successions of steps as fall within the scope of the appended claims.

In the accompanying drawings which form a part of this invention—

Figure 1 is a side elevation of a bead embodying my invention showing an attaching wire therein.

Figure 2, a section of the same on line 2—2 of Figure 1,

Figure 3, a section on line 3—3 of Figure 2,

Figure 4, a perspective view of the partition disk,

Figure 5, a diametrical section of a modified form of my invention,

Figure 6, a perspective view of the disk shown in Figure 5, and

Figure 7, a side elevation of a bead embodying my invention whose surface is faceted.

Like reference characters indicate like parts throughout the views.

In detail my novel bead comprises two hollow, substantially hemispherical sections or cups 10 of light material, in this instance of celluloid. These are cut in circular blanks from a thin sheet of celluloid and cupped up by suitable dies, each blank being subjected to heat to render it temporarily pliable, to facilitate the bending operation. When dry or cool the cups set in their acquired hemispherical shape.

A substantially circular disk 12 is also

cut by suitable tools from the celluloid sheet or strip, and has a diameter substantially equal to the maximum diameter of each of the cups. By suitable dies or otherwise the disk 12 is impressed or channeled to form a diametrical groove 13. The disk is also provided with a peripheral cavity or slot 14 at each end of the groove, extending inwardly a distance not less than the thickness of the walls of the cups 12. The cutting of the disk and slots and the impression of the groove are by combined cutting and bending dies performed simultaneously.

The three described pieces are now assembled as follows, the flat edge faces 15 of the sections 10 are fastened to the opposite faces of the disk or wall 12 at the margin of the latter so that the peripheries of the three members coincide to form a continuous surface. The fastening is effected by first applying a liquid celluloid cement to the contacting portions of the members. This forms an adhesive film 18 which when dry forms an invisible union of the parts. Referring to Figures 1 to 3 inclusive a suspension wire or cord 20 is shown upon which the bead is slidably mounted. The wires passes through slots 14 of the disk 12 and within the depression 13 in the latter.

In Figure 7 the outer surfaces of the hemispherical sections of the cups 10 have facets 21 formed upon their peripheries, which is desirable in case it is sought to imitate a stone or gem.

The construction of bead shown in Figures 1 to 3 inclusive is particularly adapted to use in such articles as necklaces. When the bead is intended for use as a pendant, as in ear ornaments, the modified form of bead shown in Figure 5 is preferable. Herein the partition disk 22 is employed, which omits the slots 14 and groove 13, but adds a peripheral shoulder 24 provided with a perforation 25 to receive a suspension loop or ring.

The cups may be of any desired cross sectional contour, such as oval, and even rectangular. The partition plate may, if preferred, be annular in shape. In actual practice the partition plate is usually of different color from the cups.

I claim:

1. An ornamental bead comprising cups oppositely disposed with their cavities facing each other, and a disk disposed between

the opposed faces of the cups and cemented to the adjacent faces thereof, said bead having provision for its suspension.

2. The process of making a bead consisting in cutting from a celluloid sheet a circular partition blank, and two circular body blanks, subjecting the body blanks to heat to render the same pliable, bending the body blanks into cups, interposing the said partition blank diametrically between adjacent faces of the body blanks with its periphery flush with that of the body blanks and cementing the cups to opposite sides of the partition blank with the peripheries of the cups flush with the periphery of the disk.

3. As an improved article of manufacture, an ornamental bead designed for jewelry and comprising two opposed substantially hemispherical cups and a substantially circular disk having a diameter substantially equal to the maximum diameter of each of the cups, said disk being interposed between the flat edge faces of the cups with the peripheries of the disk and cups coinciding to form with said cups a continuous surface, the adjacent faces of the disk and cups being adhesively united, said bead having means for its suspension.

In testimony whereof I have affixed my signature.

HENRY F. JUERGENS.
